SLIDER FOR MULTIPLE OPERATED
FASTENER INSTALLATIONS

Robert C. Legat, New Britain, Conn., assignor of
one-half to United-Carr Fastener Corporation,
Cambridge, Mass., a corporation of Massachu-
setts, and one-half to G. E. Prentice Manu-
facturing Company, New Britain, Conn., a cor-
poration of Connecticut

Application August 18, 1932, Serial No. 629,325

6 Claims. (Cl. 24—205)

My invention aims to provide improvements in sliders for multiple operated fastener installations.

In the drawing which illustrates a preferred embodiment of my invention:—

Figure 1 is a front elevation of a portion of an installation showing my improved slider structure in use;

Fig. 2 is a section on the line 2—2 of Figure 1;
10 Fig. 3 is a side elevation of the installation showing a portion of the plate-like member raised to operating position as a pull-tab for moving the slider; and

Fig. 4 is an enlarged section on the line 4—4, 15 of Figure 1, of the installation showing a projection of the pull-tab extending between two fastener elements.

Referring to the specific installation illustrated by the drawing, I have shown the usual stringers 1—1 with the edge fasteners 2, my improved slider and fastener-concealing tapes 3—3, as shown in all the figures of the drawing.

My improved slider includes the usual fastener-operating means 4 shaped and arranged to engage and disengage the fasteners 2 when the slider is moved to and fro lengthwise of the stringers 1. A web 5 extends perpendicular to the top plate portion 6 of the fastener-operating means and a plate-like means extends laterally therefrom in spaced relation to the top plate portion 6. This plate-like means may be made in any desired shape and, among other things, provides a means for concealing the remainder of the slider and presenting a neat and finished appearance to the installation. One portion 7 of the plate-like means is fixed relative to the remainder of the slider and is fastened directly to the web 5. The other portion 8 of the plate-like means is pivoted to the web 5 and can be moved about its pivot, as shown in Fig. 3, thereby providing the pull-tab for operation of the slider. Thus the plate-like means provides utility as well as ornamentation.

Any suitable locking means may be used to hold the movable portion 8 in flat position. However, I have shown (Figs. 2 and 3) a projection 9 extending from the movable portion 8 and adapted to engage between two of the fastener members 2 in any suitable and well-known manner. This projection serves the double purpose of holding the movable portion in the plane of the fixed portion 7, when not in use, and of preventing movement of the slider relative to the fasteners the purposes of which are now well known to those skilled in the art.

The plate-like means need not be spaced from the top plate portion 6 except when the concealing tapes 3—3 are used. This spacing is to permit the tapes 3—3 to pass between the plate-like means and the top plate portion 5 (Fig. 2), thereby to permit easy passage of the tapes and allow the plate-like means to remain above the tapes (Figure 1) at all times.

My improved slider is simple in construction, artistic in appearance, and combines utility with art in a highly desirable manner.

While I have illustrated and described a preferred embodiment of my invention, I do not wish to be limited thereby, because the scope thereof is best defined by the following claims.

I claim

1. A slider for a multiple operable fastener installation comprising fastener-operating means for engaging and disengaging the fastener elements on opposed edges of the stringers, plate-like means carried by the fastener-operating means and divided transversely into two parts one of which is located entirely to one side of one edge of the other, said parts being shaped and arranged to conceal the fastener-operating means and to provide any suitable design appearance to the slider structure, and one part of said plate-like means being pivotally mounted as a portion of the slider for movement relative to the other part to provide a pull-tab for manipulation of said slider relative to the stringers, and said pivoted part being normally in the same plane as the remainder of the said plate-like means.

2. A slider for a multiple operable fastener installation comprising fastener-operating means for engaging and disengaging the fastener elements on opposed edges of stringers, plate-like means carried by the fastener-operating means and shaped and arranged to conceal the fastener-operating means and to provide any suitable design appearance to the slider structure and one part of said plate-like means being pivotally mounted as a portion of the slider for movement relative to the remainder thereof to provide a pull-tab for manipulation of said slider relative to the stringers, and all of said plate-like means being spaced away from the upper face of the fastener-operating means thereby providing a space permitting the passage of fastener element covering tape between it and the fastener-operating means, thereby exposing the plate-like means at all times.

3. A slider for a multiple operable fastener installation comprising fastener-operating means

for engaging and disengaging the fastener elements on opposed edges of stringers, a web extending perpendicular from the top face of said fastener-operating means, plate-like means extending laterally from said web in spaced relation to said top face, one portion of said plate-like means being fixed and another portion being hingedly connected to said web as and for the purposes illustrated and described.

10 4. A slider for a multiple operable fastener installation comprising fastener-operating means for engaging and disengaging the fastener elements on opposed edges of stringers, a projection extending perpendicularly from the top face of 15 the fastener-operating means, a plate portion attached to said projection in fixed relation thereto and a second plate portion transversely pivoted to the said projection adjacent to one 20 end of the first mentioned plate portion and below the upper edge of the fastener-operating means and being adapted to act as a pull-tab to operate the fastener means.

5. A slider for a multiple operable fastener installation comprising fastener-operating means 25 for engaging and disengaging the fastener elements on opposed edges of stringers, a web extending perpendicularly from the top face of said fastener-operating means, plate-like means extending laterally from the said web in spaced

relation to said top plate, one portion of said plate-like means being fixed and the other portion being hingedly connected to said web, said hingedly connected portion having a slot therein allowing a portion of the web to extend therethrough thereby permitting various positions of the said hingedly connected portion relative to the said fixed plate-like means.

6. A slider for a multiple operable fastener installation comprising fastener-operating means for engaging and disengaging the fastener elements on opposed edges of the stringers, plate-like means carried by the fastener-operating means and divided transversely into two parts one of which is located entirely to one side of one 15 edge of the other, said parts being shaped and arranged to conceal the fastener-operating means and to provide any suitable design appearance to the slider structure, one part of said plate-like means being pivotally mounted as 20 a portion of the slider for movement relative to the other part to provide a pull-tab for manipulation of said slider relative to the stringers, said pivoted part being normally in the same plane as the remainder of the said plate-like means, 25 and locking means carried by the pivoted part of the plate-like means to lock it in the plane of the fixed part when not in use as a pull-tab.

ROBERT C. LEGAT.
